UNITED STATES PATENT OFFICE.

CHARLES E. PEARSON, OF CHICAGO, ILLINOIS.

WINDOW-GUARD.

1,231,783.

Specification of Letters Patent.

Patented July 3, 1917.

Application filed October 28, 1916. Serial No. 128,164.

To all whom it may concern:

Be it known that I, CHARLES E. PEARSON, a citizen of the United States, and a resident of Chicago, in the county of Cook and State 5 of Illinois, have invented certain new and useful Improvements in Window-Guards, of which the following is a specification.

My invention relates to window guards and particularly to guards which are adapted 10 to be secured to the frame sill and to the sash to follow the sash when opened and to guard the opening against outsiders.

Among the important objects of the invention are to provide improved means 15 whereby the occupant may readily attach the guard to the frame sill and to the sash; to provide improved means for preventing tampering with or detachment of the securing and locking means; and to provide improved means adapted to be secured to the frame top and to the upper sash to limit the 20 opening distance of the upper sash and to guard the opening after such sash has been lowered.

On the accompanying drawings guard 25 mechanism is shown in which the features of my invention are embodied.

On the drawings

Figure 1 is an elevational view of a window frame and sash with my guard mechanism applied thereto.

Fig. 2 is an enlarged sectional view on plane 2—2, Fig. 1.

Fig. 3 is an enlarged sectional view on plane 3—3, Fig. 1.

Fig. 4 is an enlarged sectional view on plane 4—4, Fig. 1, and

Fig. 5 is an enlarged sectional view on plane 5—5, Fig. 1.

On the drawing 10 represents the sill and 40 11 the top of the window frame F, and 12 and 13 represent the upper and lower window sashes provided with panes 14 and 15.

The window guard for the lower sash comprises upper and lower horizontal bars 16 and 17 and intermediate horizontal bars 18. The intermediate bars are secured to adjacent inner pivots 19 of lazy tong structures 20. The lower links 21 and 22 of the outer 50 lazy tong structures are pivoted to the upper ends of L-shaped latch members 23 whose lower ends 24 are deflected inwardly, and at intermediate points these latch members are secured to the lower horizontal bar 17. The lower links of the intermediate lazy tong structures are pivoted to pieces 25

which are also secured to the bar 17. The upper links of the lazy tong structures are pivoted to pieces 26 which are secured to the upper horizontal bar 16. 60

For receiving the ends 24 of the latch members 23 rectangular plates 27 are provided and adapted to be secured to the sill by screws 28. The central sections of the plates are deflected upwardly to form loops 29 for receiving the ends 24, as best shown in Fig. 3. By tilting the guard inwardly the ends 24 can readily be inserted through the loops. The upper bar 16 has slots 30 at its ends for receiving the horizontal ends of 70 angle pieces 31 secured to the lower window sash. When thus supported the guard will expand as the lower sash is raised and will guard the opening, and the guard will contract when the sash is lowered. In order to 75 lock the bar 16 to the fittings 31 hasp levers 32 are pivoted to the bar 16 preferably by the same rivets 33 which secure the pieces 26 to the bar. At their outer ends these levers have vertical tongues 34 for engaging 80 through slots 35 provided in the ends of the angle pieces 31, and at their inner ends the levers have slots 36 and 37 respectively for receiving a staple 38 extending from a plate 39, the staple being inserted through the slot 85 40 in the bar 16 and through the slots 36 and 37 of the levers to receive a pad-lock 41. To release the guard from the sash the pad-lock is removed and the staple withdrawn, and the latch levers then rotated to withdraw their tongues 34 from the fittings 31, 90 and the bar 16 can be withdrawn from the fittings, and then when the guard is tilted inwardly the ends 24 can be withdrawn from the loops 29 of the sill fittings. To prevent 95 removal of the ends 24 from the loops when the guard is in service, the plates 27 have their outer ends deflected upwardly to form guard walls 42. Also to prevent outsiders from removing the screws 28 and thereby 100 releasing the plates 27, I provide guard plates 43 for the fitting plates 27, these guard plates having the central openings 44 for receiving the loops and having ears 45 by means of which they may be secured to 105 the sill by screws 46. When in place these guard plates will cover up the screws 28 of the sill plates 27. The screws 46 could, of course, be removed from the outside but the ends 24 of the guard will still hold the guard 110 plate over the plates 27 to protect the screws 28. The screws 46 are provided merely to

hold the guard plates in place to prevent accidental removal thereof when the guard is removed from the window. With the arrangement described the guard can readily be inserted and secured to then follow the movements of the lower sash or can be readily removed, and after being secured it will be impossible for outsiders to enter or to remove the guard. Preferably the fittings 5 31 are secured to the lower sash sides a distance upwardly from the bottom of the window so that the window sash will prevent an outsider from getting at the screws by which the fittings 31 are secured.

15 I also provide guard means for any opening left by the lowering of the upper window. As shown, a lazy tongs 47 has its lower links pivoted to a hasp 48 and its upper links pivoted to a plate 49 from which 20 extends the L-shaped latch member 50 for hooking into the loop 51 formed on a plate 52 secured in the groove 53 at the top of the window frame. A tongue 54 extends from the top of the upper sash 13 to be received 25 by the notch 55 in the hasp 48, the tongue having the hole 56 for receiving the padlock 57. Preferably, the lazy tongs are of such size as to limit the downward movement of the upper window so that an outsider cannot enter, or, a guard structure 30 similar to that for the lower sash may be provided. In order to prevent an outsider from detaching the plate 52 a guard plate 57 similar to the guard plate 43 may be provided to receive the loop 51 and to cover the 35 screws which hold the plate 52 in place.

As changes and modifications may be made which would still come within the scope of the invention, I do not desire to be limited to the exact construction and arrangement shown, and I claim the following:

1. The combination with a window frame and a window slidable therein, of a longitudinally expansible and contractible guard structure, means for attaching the guard structure to the frame, fittings secured to the sash of the window and having slots, said guard structure being slotted to receive 45 said fittings, hasp levers pivoted to said guard structure and adapted at their outer ends to enter the slots of said fittings in front of the guard structure to thereby lock the guard structure to the fittings, and 50 means for locking said levers in such locking position.

2. The combination with a window frame and a window slidable therein, of a longitudinally expansible and contractible guard 60 structure, means for attaching the guard structure to the frame, fittings secured to the sash of the window and having slots, said guard structure being slotted to receive said fittings, hasp levers pivoted to said guard 65 structure and adapted at their outer ends to

enter the slots of said fittings in front of the guard structure to thereby lock the guard structure to the fittings, and means for locking the inner ends of said levers together to prevent rotation thereof to unlock said 70 guard structure.

3. The combination with a window frame and a window slidable therein, of a longitudinally expansible and contractible guard structure, means for attaching the guard 75 structure to the frame, fittings secured to the sash of the window and having slots, said guard structure being slotted to receive said fittings, hasp levers pivoted to said guard structure and adapted at their outer 80 ends to enter the slots of said fittings in front of the guard structure to thereby lock the guard structure to the fittings, the inner ends of said levers having slots and said guard structure having a slot adapted to 85 register therewith when the levers are in guard locking position, and a pad-lock receiving staple structure extending through said registering slots to lock the inner ends of the levers to the guard structure and 90 against unlocking rotation.

4. The combination with a window frame and a window slidable therein, of a guard structure comprising upper and lower horizontal bars, expansible members connected 95 with said bars to permit movement thereof toward or away from each other, means for attaching the lower bar to said frame, slotted fittings secured to the window sash, said upper bar having slots for receiving said 100 fittings, latch levers pivoted to said upper bar and having tongues at their outer ends for entering the slots of the fittings in front of said upper bar to lock said upper bar to the 105 fittings, and means for locking said levers in such bar locking position.

5. The combination with a window frame and a window slidable therein, of a guard structure comprising upper and lower horizontal bars, expansible members connected 110 with said bars to permit movement thereof toward or away from each other, means for attaching the lower bar to said frame, slotted fittings secured to the window sash, said upper bar having slots for receiving said 115 fittings, latch levers pivoted to said upper bar and having tongues at their outer ends for entering the slots of the fittings in front of said upper bar to lock said upper bar to the 120 fittings, and means for locking the inner ends of said levers to said upper bar to permit rotation thereof to unlock said upper bar from said fittings.

6. The combination with a window frame and a window slidable therein, of a guard 125 structure comprising upper and lower horizontal bars, expansible members connected with said bars to permit movement thereof toward or away from each other, means for attaching the lower bar to said frame, slot- 130

ted fittings secured to the window sash, said upper bar having slots for receiving said fittings, latch levers pivoted to said upper bar and having tongues at their outer ends 5 for entering the slots of the fittings in front of said upper bar to lock said upper bar to the fittings, the inner ends of said levers overlapping and having slots, and said upper bar having a slot adapted to register 10 with said lever slots when said levers are in locking position, and a staple member for engaging through the registering slots to receive a pad-lock whereby said levers will be locked in position to lock said upper bar 15 to said fittings.

7. The combination with a window frame and a window slidable therein, of a guard structure comprising upper and lower horizontal bars and intermediate horizontal bars, 20 lazy tong structures connected to said upper and lower bars and pivoted to said intermediate bars, fittings secured to the frame sill and extensions on said lower bar for engaging in said fittings to attach the bar 25 to the sill, hasp members secured to the sash, said upper bar being slotted to receive said hasps, and latch levers pivoted to the upper bar and having tongues for engaging in said hasps in front of the upper bar to lock the 30 bar to the hasps.

8. The combination with a window frame and a window slidable therein, of an expandible guard structure attached at its upper end to the sash, fitting plates secured to 35 the sill and having loops therein, L-members secured to the guard structure for hooking into said loops to attach the guard structure to the sill, and guard plates on said fitting plates for preventing removal of said fitting 40 plates from the sill when said guard structure is in position.

9. The combination with a window frame

and a window slidable therein, of a guard structure attached at its upper end to the sash, fitting plates screwed to the sill and 45 having loops, tongues extending from the lower end of said guard structure for hooking into said loops to attach the guard structure to the sill, and guard plates having 50 openings to receive said loops and extending over the fitting plates to cover the screws to thereby prevent access to the screws and removal of the fittings when the guard structure is in place.

10. The combination with a window 55 frame and a window slidable therein, of a guard structure, fitting plates secured to the sash by nails or screws, guard plates over said fitting plates to cover the nails or screws, a section of each fitting plate being 60 deflected to form a loop, said guard plates having openings through which said loops project, tongues extending from said guard structure to hook into said loops to attach the guard structure to the sill, means for 65 attaching said guard structure to the sash, the outer ends of said sill fitting plates being deflected upwardly to prevent withdrawal of said tongues from said loops when the guard structure is secured to the sash. 70

11. The combination with a window frame and a window slidable therein, of an expandible guard structure having a slot at one end and a tongue at its other end, a hasp extending from the sash of the window for 75 extending through said slot to receive a pad-lock, and a fitting secured to the frame provided with a loop for receiving said tongue.

In witness whereof I hereunto subscribe 80 my name this 24th day of October, A. D., 1916.

CHARLES E. PEARSON.
